UNITED STATES PATENT OFFICE.

JOHN HENRY HOWARTH, OF LANETT, ALABAMA, ASSIGNOR TO WEST POINT MANUFACTURING CO., OF LANGDALE, ALABAMA, A CORPORATION OF ALABAMA.

BAG FABRIC.

Original application filed December 30, 1924, Serial No. 758,821. Divided and this application filed May 4, 1925. Serial No. 27,827.

This invention relates to fabrics, more particularly to woven bag fabrics, and is a division of a co-pending application, Serial No. 758,821, filed Dec. 30, 1924.

5 An object of the invention is to provide a fabric having a plurality of series of tubular bag sections separated by a longitudinal portion forming the bag bottoms, and by transversely extending portions which separate 10 the sections. The tubular sections are open at the fabric edges to form the bag mouths, and the fabric is provided at each edge with a selvage whereby each section, as woven, constitutes a finished bag.

15 It is broadly old in the art to provide a bag fabric of this general character, as is illustrated, for example, in the patent to Grauwiler, 264,526, Sept. 19, 1882. The present invention, however, marks a distinct improvement over the fabric of this patent in the provision of selvage edges which eliminate the necessity for hems of tubular construction or otherwise formed, and also in the formation of the longitudinally extending 20 separating strip between the two bag sections as will be described in detail.

In the accompanying drawings there is shown one embodiment of the invention, and in these drawings:

30 Figure 1 is a diagrammatic face view of the fabric.

Figure 2 is a longitudinal sectional view on the line 2—2 of Figure 1.

Figure 3 is a cross sectional view along 35 the line 3—3 of Figure 1, illustrating the weave of the central division strip, and

Figure 4 is a transverse sectional view on the line 4—4 of Figure 1.

Referring to the drawings in detail, 40 indicates tubular bag sections arranged in two parallel series which are separated by an intermediate longitudinal portion 11 of different weave, and which forms the closed bottoms of the bag sections. At the edges of the fabric, the tubular sections are open (Figure 4) to form bag mouths 12, and each layer is provided with a selvage 13, whereby the bag may be completely woven in the loom, and it is unnecessary to hem or otherwise form the bag mouths to prevent raveling. The several sections are separated by transverse portions 14, which extend entirely 45 across the fabric and are of different weave

from the tubular sections. Preferably, both the transverse portions 14 and the longitudinal portion 11 are of tape-like formation which is obtained by uniting the warps of the upper and lower plies of the tubular sections. The transverse portions 14 will not be described in detail, since they may be of any ordinary formation, but referring to the longitudinal division strip 11 (Figure 3), it will be noted that the same has an intermediate portion 11' which is more loosely woven than the remainder, and in which the warps are more widely spaced. That is to say, the portion 11 has at each side of the intermediate zone 11' more closely woven sections 11'' which constitute the bag bottoms, and the loosely woven zone serves as a division line along which the two series of bag sections may be separated in the loom or after the fabric has been removed from the loom.

This fabric is preferably woven in the loom of my copending application, above referred to, which is provided with two sets of four harnesses arranged side by side, whereby the weft threads may cross at the center of the fabric within the longitudinal portion 11. In Figure 3, the cross of the weft threads is illustrated. At each side of the central portion or strip 11, the fabric is formed into upper and lower plies 15, 16. It will be noted that the second and fourth picks 17, 18, remain in the lower and upper plies respectively. The first pick 19 is in different plies at opposite sides of the center strip 11, and the third pick 20, likewise crosses from one ply to the other at opposite sides of the longitudinal dividing portion 11. By thus crossing the weave, the fabric is closed at its center in a single shuttle loom, and thereby there is provided the fabric having two parallel series of bag sections with the mouths 90 of the section open at the sides of the fabric.

Obviously, changes may be made in the particular weave without departing from the invention which is defined in the following claim.

I claim:

As a new article of manufacture, a bag fabric comprising two parallel series of tubular bag sections, both sides of the fabric being open to form the bag mouths, transversely disposed portions of different weave

separating said sections, and a longitudinally extending centrally disposed section of different weave separating said two series, said longitudinally extending section being woven to form two spaced tape portions which constitute the bag bottoms, said tape portions being separated by an intermediate

part provided with warp threads which are spaced apart a greater distance than the warp threads of said tape portions whereby ¹⁰ to provide a division line.

In testimony whereof I have hereunto set my hand.

JOHN HENRY HOWARTH.
